UNITED STATES PATENT OFFICE.

MONTRAVILLE M. WOOD, OF SCHENECTADY, NEW YORK, ASSIGNOR TO
GENERAL ELECTRIC COMPANY, A CORPORATION OF NEW YORK.

TROLLEY-EAR.

SPECIFICATION forming part of Letters Patent No. 795,016, dated July 18, 1905.

Application filed January 15, 1903. Serial No. 139,214.

To all whom it may concern:

Be it known that I, MONTRAVILLE M. Wood, a citizen of the United States, residing at Schenectady, county of Schenectady, 5 State of New York, have invented certain new and useful Improvements in Trolley-Ears, of which the following is a specification.

My invention relates to overhead trolley suspension, and has for its object the provision of a highly-efficient detachable ear which 10 will clamp the wire throughout the length of the ear and also be readily attached and disconnected.

My invention will be more readily understood by reference to the accompanying drawings, forming a part of this specification, in which—

Figure 1 is a side elevation of an ear embodying one form of my invention applied to 20 a section of grooved wire. Fig. 2 is a central transverse section of the ear and wire, showing the tension-wrenches in position. Fig. 3 is a similar section showing a locking-bolt in position. Fig. 4 is an enlarged perspective 25 view of the locking-bolt. Fig. 5 is an enlarged bottom plan of the ear, and Fig. 6 is an enlarged transverse section of clamping member.

The ear shown in the drawings consists of a 30 main retaining member A and two longitudinally-movable clamping members B, carried by the retaining member A and adapted to grip the trolley-wire between them. The retaining member A consists of an elongated 35 head 1 and a central boss 2, provided with a tapped hole 3 for engaging the threaded end of the ordinary insulated supporting-bolt. The head 1 has transverse stiffening-ribs 4 and webs 5 between its upper edge and the 40 sides of the boss 2 and is provided in its lower part with a longitudinal groove circular in cross-section, with its axis somewhat above the bottom edge of the head 1, whereby inwardly-projecting shoulders 6 are formed 45 upon the head. A central transverse hole 7 is provided in the head 1 at the base of the boss 2 and intersecting with the upper part of the longitudinal groove. The clamping members B have their upper portions formed

with substantially semicircular cross-sections 50 and of a size that when placed together with their flat sides in contact they will fill the longitudinal groove in the head 1. The lower portions of the clamping members B are recessed to form jaws 8 at their lower edges and 55 are set askew or obliquely with relation to their upper portions—that is to say, the jaw 8 of each member B has one end near the plane of the flat side of the upper member and gradually retreats therefrom toward the 60 opposite end, where it is removed from said plane a considerable distance, as indicated in Figs. 5 and 6. As a result of this arrangement of the jaws 8 relatively to the upper portions of the clamping members they stand 65 at an angle to their paths of travel through the retaining member A and accordingly approach or recede from each other when moved in opposite directions.

The clamping members B may be made 70 with uniform cross-sections, and the lower or jaw edge may be set askew by offsetting, and as a consequence I am able to use drawn or squirted metal for these parts.

The means shown for moving the clamping 75 members B relatively to each other in the retaining member A consists of rack-teeth 9, provided in the upper edges of the clamping members B, and wrenches 10, adapted to engage the teeth 9 through holes 7 and consisting of pinions 11, carried at the ends of short arbors 12, provided at the outer ends with handle-bars 13.

When it is desired to connect a trolley-wire to the ear, the right-hand clamping 85 member of Fig. 5 is moved down and the left-hand member moved up until the space between the jaws 8 will admit the wire. Then the clamping members B are moved in the opposite direction until the jaws 8 securely 90 grip the wire. The wrenches are then removed, and a locking-bolt 14 may be inserted in the hole 7. The bolt 14 is an ordinary bolt having two longitudinal grooves 15 cut therein, whereby a tongue 16 is formed which 95 enters a notch between two rack-teeth 9 on each clamping member, and is provided with a cotter-pin 17 at its end.

- It is to be noted that with my construction the retaining member may be made as long as desired and the wire effectually clamped thereto at every point throughout the length of the member, that the clamping members may be of drawn or squirted metal and accordingly inexpensively made, and that the ear may be connected to or disengaged from the wire with a minimum effort.
10. My invention is in no way restricted to the construction shown in the drawings and may be changed and modified in many respects without departing from the spirit or scope thereof.
15. What I claim as new, and desire to secure by Letters Patent of the United States, is—
1. The combination of a retaining member and a clamping member movable longitudinally thereof and provided with a jaw set obliquely to its path of travel.
  2. The combination of a retaining member, a clamping member movable longitudinally thereof and provided with a jaw set obliquely to its path of travel, and means for moving said clamping member.
  3. The combination of a retaining member, a clamping member movable longitudinally thereof and provided at its lower edge with an oblique jaw and at its upper edge with teeth, and means for engaging said teeth and moving said clamping member relatively to said retaining member.
  4. The combination of a retaining member, and two like clamping members movable longitudinally of said retaining member into operative engagement with the wire supported thereby.
  5. The combination of a retaining member and two clamping members movable longitudinally thereof and provided with jaws set obliquely to their paths of travel.
6. The combination of a retaining member provided with a longitudinal groove, and two like clamping members independently movable in said groove and adapted to be brought into operative engagement with the wire by said movement.
7. The combination of a retaining member provided with a longitudinal groove, and two clamping members movable in said groove and provided with oblique jaws.
8. The combination of a retaining member provided with a longitudinal groove, and two clamping members independently movable in said groove and provided with oblique jaws.
9. The combination of a retaining member provided with a longitudinal groove, two clamping members movable in said groove, and means for independently moving said clamping members.
10. The combination of a retaining member provided with a longitudinal groove, two clamping members movable in said groove and provided at their upper edges with teeth and at their lower edges with oblique jaws, and means for engaging said teeth and moving said clamping members in opposite directions.

In witness whereof I have hereunto set my hand this 13th day of January, 1903.

MONTRAVILLE M. WOOD.
